UNITED STATES PATENT OFFICE.

GUSTAF JOHNSON, OF MARQUETTE, MICHIGAN.

SLED-RUNNER.

SPECIFICATION forming part of Letters Patent No. 694,753, dated March 4, 1902.

Application filed November 20, 1901. Serial No. 82,965. (No model.)

To all whom it may concern:

Be it known that I, GUSTAF JOHNSON, of Marquette, in the county of Marquette and State of Michigan, have invented certain new and useful Improvements in Sled-Runners; and I do hereby declare the following to be a full, clear, and exact description of the invention, such as will enable others skilled in the art to which it appertains to make and use the

same.

The object of this invention is to provide an improved sled-runner capable of adjustment for use on vehicles of different sizes. It is primarily designed for attachment to go-carts for children.

The invention will be hereinafter fully set forth, and particularly pointed out in the claims.

In the accompanying drawings, Figure 1 is a view in side elevation of a runner constructed in accordance with my invention. Fig. 2 is a plan view of two runners.

Referring to the drawings, 1 1 designate sled-runners suitably shaped to insure resiliency, their forward upwardly-curved ends terminating in depending vertical arms 2.

3 designates a right-angular or L-shaped bar, the upright arm 4 of which is held in engagement with the vertical arm 2 of one of the runners by a clip 5 and bolt 6. On the other or horizontal arm is a hub or binding-sleeve 7, held by a bolt 8 and having a clamp 9, designed to receive and be clamped on the front axle of the vehicle.

10 designates the hubs or binding-sleeves by which the rear ends of the runners are secured to the rear axle.

In practice the runners are preferably positioned at the outer ends of the front hubs or sleeves 7 and at the inner ends of the rear hubs or sleeves 10. By this means the runners may be readily attached to any vehicle whose rear axle is of greater length than the front one, yet be maintained truly parallel.

When it is desired to adjust the runners to vehicles of different heights, the clips 5 are loosened 3 and bars moved up or down with relation to the arms 2 of the runners. To shorten the runners—that is, to bring the holding-points closer together to conform to go-carts whose axles are not far apart—the bolts 8 are loosened and the hubs 7 moved

toward the rear ends of the horizontal arms of bars 3, and to increase the distance between the holding-points the sleeves are 53 moved in the opposite direction. When this latter adjustment is insufficient, clips 5 may be loosened and bars 3 reversed, as shown in dotted lines, Fig. 1, thereby allowing the hubs 7 to be moved a greater distance from 60 the hubs 10.

The advantages of my invention are apparent. It will be seen that I have provided simple and efficient means by which sled-runners may be readily adjusted both longitudinally and vertically and that this adjustment is simple and easily effected. It will also be noted that I dispense with the use of braces between the runners, as the binding-sleeves hold them securely without 70 additional means.

Although the invention is primarily designed for "go-carts," it is obvious that it is not restricted to such use.

I claim as my invention—

1. The combination with a pair of sled-runners, and means for securing the front and rear ends of the runners, of an independent member intermediate each runner and one of its securing means having a horizontal portion upon which such securing means are adjustably mounted to regulate the distance between itself and the other securing means, and means whereby such horizontal portion may be axially turned to project forward or 85 rearward of its axis to increase the extent of adjustment of the securing means toward or away from each other, as and for the purpose set forth.

2. The combination with a pair of sled-runners and means for securing the front and rear ends of the runners, of right-angular bars intermediate each runner and one of its securing means, having each one arm adjustably held to such securing means, substantially as set forth.

3. The combination with a runner secured at one end and having a vertical portion at or near its other end, of an angular bar having one arm adjustably secured to said vertical portion, and holding means adjustable on the other arm of such bar by which the runner is held, substantially as set forth.

4. The combination with a runner held at

one end, of means for holding the other end of the runner comprising a hub, a set-screw, and a clamp, and an angular bar one arm of which is secured to the runner and to the other arm of which the hub is adjustably held by its set-screw, substantially as set forth.

5. The combination with a pair of sled-runners, of clamps designed to hold said runners on the front and rear axles of a vehicle, said runners being secured at their rear ends to the inner ends of the rear clamps, angular bars having vertical and horizontal arms, means adjustably securing such vertical arms

to the forward ends of the runners, and means adjustable on the horizontal arms of such bars for locking the same to the outer ends of the front clamps, substantially as set forth.

10 In testimony whereof I have signed this specification in the presence of two subscribing witnesses.

GUSTAF JOHNSON.
